ADJUSTING DEVICE

Alexey J. Stepanoff, Phillipsburg, N. J., assignor
to Ingersoll-Rand Company, New York, N. Y., a
corporation of New Jersey

Application October 8, 1942, Serial No. 461,280

1 Claim. (CL 170—163)

This invention relates to pumps, and more particularly to an adjusting device for selectively varying the pitch of the vanes of a rotary pump.

One object of the invention is to minimize wear upon the elements serving to adjust the vanes.

Other objects will be in part obvious and in part pointed out hereinafter.

In the drawings accompanying this specification and in which similar reference numerals refer to similar parts,

Figure 1 is an elevation of a centrifugal pump of a type to which the invention may be advantageously applied and a foundation, shown in section, to support the pump.

Figure 2 is an elevation, partly in section, of an enlarged view of the pump illustrating the manner in which the invention may be applied thereto.

Figures 3 and 4 are transverse views taken through Figure 2 on the lines 3—3 and 4—4, respectively, and

Figure 5 is a view similar to Figure 2 showing a modified form of the invention.

Referring more particularly to the drawings, and at first to Figure 1, the pump, designated in general by 20, is of the vertical, axial-flow type and shown extending into a pit 21 defined by a foundation 22 for pumping liquid 23 from the pit.

The casing 24 of the pump is shown as consisting of ring-like sections, a number of which lie within the pit 21 and one section designated 25 lies above the pit 21 and has a flange 26 to seat upon the foundation 22 for supporting the entire pumping mechanism. On the upper end of the casing section 25 is a motor 27, only a portion thereof being shown, for driving the rotative parts of the pump 20.

The pump is of the vertical type and the lowermost end of the casing 24 is flared to define a wide inlet opening 28 for the admission of liquid into the casing 24. The pump is also provided with a suitable outlet 29 shown as leading from the casing section 25.

Arranged within the casing 24 and in coaxial relationship therewith are upper and lower support members 30 and 31 that are spaced with respect to each other and connected to the casing 24 by ribs 32. In the uppermost support member 30 is a bearing 33 for a shaft 34 that may be secured, in a well known manner, to the shaft of the motor 27.

The shaft 34 terminates between the support members 30 and 31 and has a reduced end portion 35 that extends into a box 36 comprising a hollow body portion 37 of generally cylindrical shape

and upper and lower covers 38 and 39, respectively, that are secured to the body portion 37 by screws 40. The cover 38 has a depending, hollow extension 41 to receive the reduced end 35 of the shaft and a nut 42 threaded upon the shaft 34 acts against the lower end of the extension 41 for clamping the cover 38 against a collar 43 on the shaft 34. The box 36 is held against rotational movement upon the shaft 34 by a key 44 embedded in the extension 41 and the shaft.

The vanes 45 of the pump are supported by the box 36 and the extension 41 and these elements are respectively provided with radially extending apertures 46 and 47 to receive bearing portions 15 or stems 48 on the vanes. Between each vane 45 and its stem 48 is a collar 49 that lies in a recess 50 in the peripheral surface of the box 36 to prevent movement of the vanes in the direction of the shaft 34, and on the portions of the stems 48 lying inside of the box 36 are sleeves 51 that extend into the apertures 47 to serve as renewable wearing surfaces for the stems 48. The sleeves have collars 52 that seat against the inner surface of the box 36 and are secured to 20 the stems 48 by pins 53.

Each collar 52 has a crank pin 54 that projects from the innermost side of the collar into a slot 55 in a hollow block 56 arranged slidably, endwise, upon the extension 41. Externally, the 25 upper portion of the block 56 is of rectangular shape and the walls 57 of this portion of the block lie in the spaces 58 between the collars 52 and the extension 41 and have oblong slots 59 that extend longitudinally of the block to accommodate the sleeves 51.

The slots 59 are of only slightly greater width than the diameters of the sleeves 51 to permit free endwise movement of the block upon the extension 41 for rocking the vanes about their axes. 30 The side walls of the slots 59 will thus engage the peripheries of the sleeves 51 for holding the block against rotation with respect to the extension 41.

In practice, and as will be readily apparent 35 from the foregoing description, the adjustment of the vanes 45 is effected by moving the block 56 endwise of the extension 41. The means employed, in the present instance, for thus actuating the block are operated by manual force applied 40 through an operating device 60 located at a point remote from the vanes, as for example upon the flange 26 of the pump 20.

The operating device 60 may be of any suitable type to impart reciprocatory movement to a 45 rod 61 extending from the said device along the

exterior of the casing 24 to a point below the inlet opening 28. The lower end of the rod 61 is pivotally connected to an end of a lever 62 having its opposite end pivotally connected to a lug 63 at the inlet end of the casing 24. The lever 62 lies across the end of the casing 24 and its intermediate portion is pivotally connected to a rod 64 arranged in tandem with the shaft and slideable in the support member 31 and extending into the lower portion of the box 36 to a point near the lower end of the shaft 34.

As will be readily appreciated, during the operation of the pump, the vanes 45 are subjected to great hydraulic thrust so that their stems are forced heavily against their bearing surfaces in the box 36 and the extension 41. A considerable force is required for effecting oscillatory movement of the vanes and it is, therefore, desirable that means be provided to reduce friction between the rotary and non-rotary elements serving to actuate them in order that the cooperating bearing surfaces of such elements may be protected against undue wear. To this end a thrust bearing 65 is employed as the connecting element between the rod 64 and the block 56 to transmit the movement of the rod to the block. The thrust bearing is of the anti-friction type. It is arranged in the lower end of the block 56 which is accordingly provided with a recess 66 to accommodate its outer race 67. The inner race 68 is disposed upon a stem 69 on the upper end of the rod 64, and a nut 70 threaded upon the end of said stem clamps the inner race 68 firmly to the rod. A cover plate 71 fastened to the lowermost end of the block 56, by screws 72, clamps the outer race 67 fixedly in position in the recess 66.

In the form of the invention shown in Figure 5 the thrust bearing serving to transmit movement from the rod 64 to the block 56 is of the radial shoe type. It is located beneath the block 56 and preferably within the support member 31.

The block 56, in the present instance, has a depending stem 73 upon which is arranged a sleeve 74 having a collar 75 intermediate its ends, and a nut 76 threaded on the free end of the stem 73 clamps the sleeve 74 securely in position upon the stem. The collar 75 lies within a casing

11 that is disposed about the stem 73 and also houses the thrust shoes 78 on the opposite sides of the collar 75 and the radial plates 79 serving as abutments for the thrust shoes.

In the form of the invention shown the casing 11 is enclosed in a casing 80 consisting of upper and lower sections 81 and 82, respectively, and is clamped tightly therebetween by bolts 83 that extend through the upper section 81 and are threaded into the section 82 in order to prevent relative endwise movement between the casings.

The entire thrust bearing assembly, including the casing 80, is slideable longitudinally in the support member 31 whereby it is guided in axial relationship with the pump rotor, and on the upper end of the section 81 is an annular extension 84 that is suitably spaced from the adjacent portion of the stem 73 to provide a path for lubricant between the thrust bearing and the box 36. The external surface of the extension 84 is in fluid tight engagement with the bore 85 in the cover 39 whereby the extension is guided.

The opposite end of the casing 80 serves as 25 a seat for a flange 86 carried by the rod 64, and screws 87 secure the said flange to the casing 80 for connecting the rod 64 rigidly to the casing 80 so that the entire thrust bearing assembly will move with the rod 64 whenever it is intended to vary the pitch of the vanes 45.

I claim:

40 In an adjusting device, the combination of a shaft and oscillatory vanes carried by the shaft, bearing portions on the vanes, a block rotatable with the shaft and movable longitudinally thereof for oscillating the vanes to vary their impelling effect, a non-rotary actuator for the block arranged in tandem with the shaft in spaced relation thereto and being movable axially of the shaft for moving the block to oscillate the vanes, a thrust bearing connected to the block and the actuator for transmitting movement from the actuator to the block, and a casing on the opposed ends of the shaft and the actuator and rotatable with the shaft to enclose the thrust bearing and the bearing portions of the vanes.

ALEXEY J. STEPANOFF.
